Matthew W. Mitchell(57) **CLAIM**

The ornamental design for a tire-shaped refrigerator, as shown and described.

DESCRIPTION

FIG. 1 is a front perspective view of the tire-shaped refrigerator of the present invention;

FIG. 2 is a second front perspective view thereof;

FIG. 3 is a front view thereof;

FIG. 4 is a rear view thereof;

FIG. 5 is a left-side view thereof;

FIG. 6 is a right side view thereof;

FIG. 7 is a top plan view thereof; and,

FIG. 8 is a bottom plan view thereof.

The dot-dashed broken lines represent boundaries to disclaim the bottom surface of the tire-shaped refrigerator, while the broken lines represent unclaimed subject matter.
